UNITED STATES PATENT OFFICE.

THADDEUS B. KEELER, OF RAHWAY, NEW JERSEY, ASSIGNOR TO EDWARD C. JOHNSON, OF ARLINGTON, NEW JERSEY.

SIGNAL-REPEATER.

SPECIFICATION forming part of Letters Patent No. 625,559, dated May 23, 1899.

Application filed April 21, 1898. Serial No. 677,931. (No model.)

To all whom it may concern:

Be it known that I, THADDEUS B. KEELER, a citizen of the United States, and a resident of Rahway, in the county of Union and State 5 of New Jersey, have invented a new and useful Improvement in Signal-Repeaters, of which the following is a specification.

My invention relates to an improvement in signal-repeaters for indicating to the operator 10 at a signal tower or station the condition of the semaphore-arm or signal located at a distance from the tower or station under his control to regulate the movement of trains.

A practical embodiment of my invention is 15 represented in the accompanying drawings, in which—

Figure 1 represents a face view of the repeater, showing its electrical connection with a pole-changer arranged to be mechanically 20 operated by a semaphore-arm, it being understood that the semaphore-arm and pole-changer are located at a distance from the repeater. Fig. 2 is a vertical section taken through the repeater-box, showing the repeater mechanism in rear elevation; and Fig. 25 3 is a horizontal section through the repeater-box, showing the repeater mechanism in top plan.

The case of the repeater-box is denoted by 30 A. It is here shown as having a general rectangular shape, but may be made of any desired shape to form an effective housing for the mechanism within it. Its front is provided with a glass plate a, through which the 35 movements of the repeater-arm are observed. Within the casing A there is located a post B, which represents the signal-post located commonly at the side of the track at a distance from the signal tower or station, and to 40 this post B there is pivoted a small semaphore-arm C, which represents the semaphore-arm pivoted to the distant signal-post. The semaphore-arm C is made of such material or has such material fixed to it as to place it 45 under the control of magnets and is so balanced that when it is entirely free from magnetic influence it will hang in the position represented in dotted lines, as D, about midway between its normal position of danger 50 (represented in full lines in Fig. 1) and its position of safety or clear, (denoted by dotted

lines at D'.) The arm C is polarized by means of either a permanent or an electro magnet—in the present instance a permanent magnet E in proximity to the counterbalance end of 55 the arm C for the purpose of placing the opposite end of the arm under the control of an electromagnet F. (Shown in dotted lines in Fig. 1 and in full lines in Figs. 2 and 3.)

Wires f f' within the casing A lead from the 60 opposite poles of the electromagnet F to binding-posts G G', and wires h h' lead from the binding-posts G G' to contacts located at the signal-post at a distance from the tower or station where the repeater is located. The 65 wire h leads to two contact-points denoted by I I', and the wire h' leads to two contact-points denoted by i i'. The semaphore-arm at the post distant from the station or tower is denoted by C' and the post to which it is pivoted by B'. A pole-changer consisting in the 70 present instance of a pair of contact-arms K K' is pivoted at k k' to the post B' and is connected by a link k² of insulating material, which link k² is connected by a rod k³ with 75 the counterbalance end of the semaphore-arm C'. The arms K K' are in circuit with a battery L. The arrangement is such that when the semaphore-arm C' is at normal danger position (shown in full lines) the arms K 80 K' will be in contact with the points I i', completing the circuit in one direction through the electromagnet F, thereby holding the polarized arm C of the repeater in the normal danger position. (Indicated in Fig. 1.) When, 85 however, the semaphore-arm C' is thrown into the position of safety or clear, the arms K K' will be mechanically raised into the position to make contact with the points i I, the arm K making contact with the point i and the 90 arm K' making contact with the point I, thereby completing circuit in the opposite direction through the electromagnet F, and consequently repelling the polarized arm C from its position shown in Fig. 1 and attracting 95 it into the position represented at D', Fig. 1. When, however, from any cause the semaphore-arm C' fails to move its full distance from normal danger to clear or the reverse and occupies an intermediate position, the 100 arms K K' will not make contact with either set of contact-points, the circuit will be broken

through the electromagnet F, and the repeater-arm C will fall by the effect of its own balance into the neutral position, (shown at D,) thereby indicating to the signal operator in 5 his station or tower that the signal at the distance has failed to work properly.

What I claim is—

1. In combination a semaphore-arm, a pole-changer in position to be operated by the 10 movements of the semaphore-arm, a continuously-polarized repeater-arm, an electromagnet located in position to exert its influence directly upon the polarized repeater-arm for operating said repeater-arm and an electric 15 circuit including the said pole-changer, the electromagnet and a source of electric energy, substantially as set forth.
2. In combination a repeater-arm mounted

to tilt, means for imparting to the arm a state of continuous polarization, an electromagnet 20 having its poles located in proximity to the path in which the repeater-arm travels as it swings for directly operating said arm, a semaphore-arm at a distance, a pole-changer controlled by the movements of the semaphore-arm and an electric circuit including the said electromagnet, the pole-changer and a source of electric energy, substantially as set forth. 25

In testimony that I claim the foregoing as my invention I have signed my name, in presence of two witnesses, this 30th day of March, 1898.

THADDEUS B. KEELER.
